UNITED STATES PATENT OFFICE.

CLIFTON W. SHERMAN, OF BUFFALO, NEW YORK.

FRICITION DRAFT-GEAR.

1,255,238.

Specification of Letters Patent.

Patented Feb. 5, 1918.

Original application filed April 23, 1914, Serial No. 833,898. Divided and this application filed August 16, 1917. Serial No. 186,614.

To all whom it may concern:

Be it known that I, CLIFTON W. SHERMAN, a citizen of the United States, residing at Buffalo, in the county of Erie and State 5 of New York, have invented new and useful Improvements in Friction Draft-Gears, of which the following is a specification.

This invention relates to friction draft gears such as are used in railway cars for 10 relieving the same from the shock, jar and strains while coupling and drawing the cars.

The object of this invention is to provide a draft gear of this character in which the 15 frictional surfaces are more effective and the frictional engagement of the frictional elements is distributed more uniformly over these elements.

This application is a division of an application filed April 23, 1914, Serial No. 833,898.

In the accompanying drawings:

Figure 1 is a fragmentary horizontal longitudinal section showing a form of friction draft gear embodying my invention and showing the parts in the position which they occupy when the gear is in normal position. Fig. 2 is a vertical transverse section thereof taken in line 2—2, Fig. 1.

Similar characters of reference indicate corresponding parts throughout the several views.

In its general organization this friction draft gear comprises side draft sills or beams 52 which are arranged lengthwise and parallel in the lower part of the car body, a front follower 73 guided between said sills so as to be capable of moving forward and backward horizontally, a pair of 40 front stops or blocks 54 secured to the inner sides of the sills and operating to limit the forward movement of the front follower, a longitudinal friction cylinder 51 arranged between the sills and having its front end 45 open and its rear end closed by a head 56, a pair of rear stops or blocks 53 arranged on the inner sides of the sills and operating to limit the rearward movement of the friction cylinder, a car coupler 6 provided with a 50 draw bar or shank 84 arranged lengthwise in front of the front follower, and a yoke 55 connected with the draw bar and slidably embracing the front follower and friction cylinder.

55 A solid or one-piece wedge 74 is arranged

between the members 75 of a set of friction shoes which engage the bore of the cylinder 51. The inward movement of the latter is resisted by a heavy main spring 76 interposed between the inner ends of the shoes 60 75 and the head 56 at the inner end of the cylinder, and the inward movement of the wedge is resisted by a light releasing spring 77 interposed between the inner end of the wedge 74 and said cylinder head. The 65 outer end of the wedge bears against the inner side of the front follower 73 which engages the front stops 54 on the sills while the rear head of the cylinder engages the rear stops 53 on the sills. The shank 84 70 of the draw bar engages the outer or front side of the follower 73 and is connected with the yoke 55 engaging with the rear side of the cylinder head. The rear part of the wedge is provided with inclined surfaces 78 of a comparatively low or acute angle adapted to stand close to similarly inclined surfaces 79 on the rear part of the opening inner transverse sides of the shoes 80 while the front or outer part of this wedge 80 is provided with inclined faces 80 of a comparatively high or obtuse angle which are adapted to engage with correspondingly-inclined faces 81 on the front parts of the shoes. Between the wedge 74 and the shoes 85 75 transversely operating spring means are arranged whereby the shoes are caused to bear with a greater frictional pressure against the cylinder as the wedge moves inwardly during a buffing or pulling action. 90 This transverse spring means may be variously constructed but preferably comprises a plurality of bow springs 82 made of flat spring metal, each of these springs bearing with its crown against one of the inclined 95 inner faces 28 of the wedge 74 while the ends of this spring are arranged in a recess or pocket 83 formed in the inner side of the respective shoe. The inner end of the wedge is preferably enlarged and provided with 100 forwardly facing inclined surfaces 90 arranged opposite rearwardly inclined faces 91 on the inner ends of the shoes 75, as shown in Fig. 1. By this means the wedge upon being pushed outwardly or forwardly 105 under the action of the releasing spring 77 will be engaged with the shoes so that the latter operate as stops and are pressed against the inner side of the cylinder so as to avoid chattering noise.

During the first part of the inward movement of the wedge when subjected to a buffing or pulling blow, its inner inclined surfaces 78 first compress the springs 82 and cause the latter to bear with increased friction against the cylinder, the shoes being held practically at rest against inward longitudinal movement by the resistance of the main spring 76. After the wedge has moved inwardly until its inner inclined surfaces 78 nearly engage the corresponding surfaces of the shoes, the transverse springs 82 have reached the limit of their compression and at this time the outer or front inclined faces 80 of the wedge engage with the corresponding front inclines of the shoes and operate both to increase the frictional engagement of the latter with the bore of the cylinder and also to push the same inwardly. During the last portion of the inward movement of the wedge under the buffing or pulling blow the shock is absorbed gradually by the increased frictional engagement of the shoes with the cylinder and the combined longitudinal spring resistance of the main and releasing springs 76, 77. After the blow is exhausted the releasing spring 77 pushes the wedge outwardly which relieves the lateral pressure of the shoes against the cylinder, thereby permitting the main spring to expand and push the shoes forwardly without undue recoil during the relaxation of the springs.

Owing to the extreme simplicity of this construction the same can be produced at low cost and it is not liable to get out of order under the most severe service.

I claim as my invention:

1. A frictional draft gear comprising a member having a friction surface, a set of friction shoes in frictional engagement with said member, a wedge movable lengthwise forwardly and rearwardly between said shoes, longitudinally operating spring means which resist the rearward movement of said wedge and shoes, and transversely

operating spring means interposed between the outer sides of said wedge and the inner sides of said shoes.

2. A frictional draft gear comprising a member having a friction surface, a set of friction shoes having their outer longitudinal sides in frictional engagement with said friction member and their inner longitudinal sides provided with recesses, a wedge movable lengthwise between said shoes, longitudinal operating spring means which resist the rearward movement of said shoes and wedge, transversely operating spring means arranged in said recesses and engaging with said wedge, those parts of said shoes and wedges near to said longitudinally operating spring means being inclined at a comparatively acute angle and adapted to engage with each other as the wedge effects the initial part of its rearward movement, and those parts of the wedge and shoes remote from said longitudinally operating spring means being inclined at a less acute angle and adapted to engage each other after the wedge has effected the initial part of its rearward movement causing the shoes to move rearwardly with the wedge during the last part of the rearward movement of the latter. 75

3. A friction draft gear comprising a friction member, shoes engaging the inner surfaces of said member, spring means resisting the inward motion of said shoes relatively to said friction member, a wedge arranged between said shoes and provided with acutely inclined intermediate surfaces which are opposite the inner sides of said shoes, acutely inclined outer surfaces which are opposite the outer ends of the shoes and an enlarged inner end opposite the inner ends of the shoes, spring means interposed between said wedge and cylinder, and spring means interposed between said wedge and said shoes. 80 85

CLIFTON W. SHERMAN.
